UNITED STATES PATENT OFFICE.

THOMAS P. GREGER, OF PHILADELPHIA, PENNSYLVANIA.

DESIGN FOR A MANHOLE-COVER FRAME.

SPECIFICATION forming part of Design No. 30,694, dated May 2, 1899.

Application filed April 6, 1899. Serial No. 712,019. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover Frame, of which the following is a specification, reference being had to the accompanying drawings, forming part hereof, in which--

Figure 1 is a top or plan view of a manhole-cover frame embodying my design, and Fig. 2 is a cross-sectional view on the line *x-x* of Fig. 1, these two views being deemed essential or necessary for the proper illustration and understanding of the design of my said invention.

The leading feature of my design for a manhole-cover frame consists of the particular shape or configuration and outline of the frame, as hereinafter described and claimed.

Referring to the drawings, *a* represents a base-plate provided with an opening *a'*, surrounded by an annular upwardly-projecting flange or rim *a²* of a less diameter than the opening *a'* and of conical or converging form. Integral with the plate *a* is an annular up-

wardly-projecting wall *c* of larger diameter than the opening *a'* and forming between the flange or rim *a²* and wall *c* a chamber or space *d*. The wall *c* is provided with an inwardly-projecting ledge or flange *e*, forming a seat for a cover. At or near the base of the wall *c* are provided openings *f*, extending from the outside of the wall *c* to the chamber or space *d*. The wall *c* is reinforced by radial ribs *g* of substantially triangular shape and the apices of which ribs terminate, as at *g'*, below the top of the wall *c* of the frame *A*, all as clearly illustrated in Fig. 2 of the drawings.

Having thus described my invention, what I claim as new, and desire to secure by Letters Patent, is—

The design for a manhole-cover frame, substantially as herein shown and described.

In testimony whereof I have hereunto set my signature in the presence of two subscribing witnesses.

THOMAS P. GREGER.

Witnesses:

J. WALTER DOUGLASS,
THOMAS M. SMITH.
